US0D1109795S

(12) **United States Design Patent** (10) Patent No.: **US D1,109,795 S**
(45) Date of Patent: ** Jan. 20, 2026

(54) **GOGGLES**

(71) Applicant: **JRD COMMUNICATION (SHENZHEN) LTD.**, Shenzhen (CN)
(72) Inventors: **Meiqi Wang**, Guangdong (CN); **Yan Zhu**, Guangdong (CN)

(73) Assignee: **JRD COMMUNICATION (SHENZHEN) LTD.**, Guangdong (CN)

(**) Term: **15 Years**

(21) Appl. No.: **35/522,982**

(22) Filed: **Oct. 29, 2024**

(80) **Hague Agreement Data**

Int. Filing Date: **Oct. 29, 2024**

Int. Reg. No.: **DM/241703**

Int. Reg. Date: **Oct. 29, 2024**

Int. Reg. Pub. Date: **Nov. 15, 2024**

(30) **Foreign Application Priority Data**

Apr. 30, 2024 (CN) 202430256730.2

(51) **LOC (15) Cl.** **16-06**

(52) **U.S. Cl.**

USPC **D16/314**

(58) **Field of Classification Search**

USPC D16/300, 311, 313–317, 319–321, D16/323–327, 329

CPC G02C 3/003; G02C 11/00; G02C 5/02; G02C 5/146; G02C 5/00; G02C 5/008; G02C 5/08; G02C 11/12; G02C 2200/14

See application file for complete search history.

Primary Examiner — Maria J. Edwards

(74) Attorney, Agent, or Firm — PV IP PC; Wei Te Chung

(57) **CLAIM**

The ornamental design for goggles as shown and described.

DESCRIPTION

1. Goggles

2. Goggles

1.1 : Front

1.2 : Back

1.3 : Left

1.4 : Right

1.5 : Top

1.6 : Bottom

1.7 : Perspective

1.8 : Perspective

1.9 : Perspective

1.10 : Perspective

2.1 : Front

2.2 : Back

2.3 : Left

2.4 : Right

2.5 : Top

2.6 : Bottom

2.7 : Perspective

2.8 : Perspective

2.9 : Perspective

2.10 : Perspective

Design 1: Figs. 1.1-1.10 show a first embodiment of the goggles; design 2: Figs. 2.1-2.10 show a second embodiment of the goggles.

1 Claim, 20 Drawing Sheets
